United States Patent Office

Des. 194,838
Patented Mar. 19, 1963

194,838

CHAIR

Clara A. Ridder, Greensboro, and Byron S. Clapp, Siler City, N.C., assignors to Boling Chair Company, Siler City, N.C.

Filed Apr. 13, 1962, Ser. No. 69,698

Term of patent 14 years

(Cl. D15—1)

FIG.1

FIGURE 1 is a perspective view illustrating the front and a side of a chair embodying my new design;

We claim:

The ornamental design for a chair, substantially as shown.
